UNITED STATES PATENT OFFICE.

CHARLES P. NICOLSON, OF CHICAGO, ILLINOIS.

SKIRT-PROTECTOR.

SPECIFICATION forming part of Letters Patent No. 289,020, dated November 27, 1883.

Application filed May 2, 1883. (No model.)

To all whom it may concern:

Be it known that I, CHARLES P. NICOLSON, a citizen of the United States, residing at Chicago, in the county of Cook and State of Illinois, have invented certain new and useful Improvements in Skirt-Protectors, of which the following is a specification, reference being had therein to the accompanying drawings, in which—

10 Figure 1 is a side elevation, partly in section, of skirt-garments provided with my improved protector. Fig. 2 is a plan of the protector. Fig. 3 is a perspective of the same; and Figs. 4 and 5 are a side elevation and plan, 15 respectively, of the fastening devices.

Like letters refer to like parts in all the figures.

A represents the protector, which consists of a simple rectangular piece of gossamer provided with a loop, *a*, arranged upon the outer side, and at one end thereof, and with fastening devices *a'*, arranged along and within the longer sides, and two or more fastening devices, *a''*, arranged at its end. The fastening devices may consist of hooks or buttons; but I prefer to use the ordinary garment-clasp, which may be adapted to be secured to the protector by stitches passing through the loop *b* of the clamp, or by means of the prongs *b'* thereof, or by both.

30 This being the construction, the operation is as follows: The protector is first folded longitudinally and centrally. It is then shaped circularly and one end thereof passed through the loop *a* at the other end thereof, to such a distance as is necessary to adapt the protector

to receive skirt-garments of any size or fullness, when the fastenings *a''* are secured to the protector, so as to retain it in the size thus determined. In such shape the skirt-garments 40 are arranged within the folds of the protector, and the fastening devices *a'* are secured in the usual manner to the inner and the outer skirts of the wearer.

It will thus be seen that a protector which 45 is not cumbersome, and which is readily attached and detached, and adjusted to dresses of varying sizes, is provided. It is apparent that the ends of the protector may be secured together, and the fastening devices *a'* secured 50 to the inner skirt before longitudinally folding the protector and securing its opposite edge to the outer skirt.

Having described my invention and its operation, what I claim is—

1. As a new article of manufacture, an adjustable skirt-protector comprising a rectangular piece of water-proof material provided with fastening devices along its opposite longer edges, and with means for varying the 60 size of the protector lengthwise, substantially as shown and described.

2. The combination of the water-proof protector A, provided with the fastening devices *a'* and the loop *a*, and the end fastening devices, *a''*, substantially as shown and described.

In testimony whereof I affix my signature in presence of two witnesses.

CHAS. P. NICOLSON.
